United States Patent Office.

CHARLES B. KNAPP, OF WATERLOO, WISCONSIN.

Design No. 4,302, dated August 23, 1870.

DESIGN FOR JOINING WOOD.

The Schedule referred to in these Letters Patent and making part of the same

To all whom it may concern.

Be it known that I, CHARLES B. KNAPP, of Waterloo, in the county of Jefferson and in the State of Wisconsin, have invented a new and useful Improvement in Designs for Joining Wood; and do hereby declare that the following description, taken in connection with the accompanying drawing hereinafter referred to, forms a full and exact specification of the same, wherein I have set forth the nature and principles of my said improvement, by which my invention may be distinguished from others of a similar class, together with such parts as I claim and desire to secure by Letters Patent.

The nature of my design is fully represented in the accompanying illustration, to which reference is made.

I claim as my invention—

The design for joining wood, as shown.

In testimony that I claim the foregoing, I have hereunto set my hand this 30th day of March, A. D. 1870.

CHARLES B. KNAPP.
